UNITED STATES PATENT OFFICE.

HALLEY C. DOLAN, OF DETROIT, MICHIGAN.

AUTOMOBILE-SIGNAL.

1,236,152.

Specification of Letters Patent.

Patented Aug. 7, 1917.

Application filed June 26, 1916. Serial No. 105,810.

To all whom it may concern:

Be it known that I, HALLEY C. DOLAN, a citizen of the United States of America, residing at Detroit, in the county of Wayne

5 and State of Michigan, have invented certain new and useful Improvements in Automobile-Signals, of which the following is a specification, reference being had therein to the accompanying drawings.

10 This invention relates to automobile signals, and more particularly to that type electrically controlled, to display one or more signs, and indicate direction of travel or other traffic conditions.

15 One of the objects of my invention is to provide a signal of the above type embodying a rotary sign display member held to normally display a "safety first" or "clear" signal, said rotary sign display member

20 being actuated by electrical devices selectively placed in operation to rotate the sign display member whereby a desired sign will be displayed. Such signs may be arrows indicating "right" and "left," the word "Stop" or any indicia that will indicate to the chauffeur or driver of an automobile that the signal carrying automobile is about to stop or turn into a different lane of travel.

25 Another object of my invention is to provide an electrically operated traffic signal embodying a plurality of electrical devices compactly assembled in a casing adapted to withstand the forces of nature and protect the mechanism therein from dust, dirt and other foreign matter. The casing contains illuminating means for signs displayed thereby at night, and the same illuminating means constitutes a tail light for an automobile or similar vehicle.

30 Other features of my invention will hereinafter appear as the structural details of the signal are considered, and reference will now be had to the drawings, wherein—

35 Figure 1 is a perspective view of an automobile traffic signal in accordance with my invention;

40 Fig. 2 is an enlarged vertical sectional view of the same;

45 Fig. 3 is a front elevation of a rotary sign display member;

50 Fig. 4 is a diagrammatic view of the electrical devices of the signal and the illuminating means thereof associated with controlling devices and a suitable source of electrical energy;

Fig. 5 is a front elevation of a portion of the signal, illustrating the electrical devices thereof, and

55 Fig. 6 is a cross sectional view of the same taken on or about the line VI—VI of Fig. 5.

The signal casing is cylindrical or drum shaped and comprises a rear wall 1 provided with a socket member 2 whereby the casing may be attached to a suitable automobile bracket (not shown).

Connected to the marginal edges of the rear wall 1 is an annular shell 3 closed by a circular front plate 4 in parallelism with the rear wall 1 and suitably connected to said shell. The front plate 4 has a concentric opening 5 and a holder 6 for a bull's eye or lens 7. The front plate 4 has a segment shaped opening above the opening 5, and this segment shaped opening is closed 75 by a transparent plate 8 held in position by a holder 9 of the front plate 4.

Connected to the rear wall 1 of the casing by bolts 10 and nuts 11 or other fastening means is a triangular shaped housing, comprising triangular shaped plates 12 and 13 disposed in parallelism and held spaced apart by the ends of the bolts 10. The bolts 10 have loose holders 14 which serve as pivots for armatures 15 in proximity to the pole pieces 16 of electro-magnets 17. The electro-magnets 17 are supported by angle brackets 18 each having one end thereof pivoted on the bolts 10. The opposite ends of the brackets 18 are adjustably held by 90 bolts 18^a, carried by yokes 18^b connected to the plates 12 and 13. A spring 18^c of each holder 14 maintains the armature 15 in proper position. The electro-magnets, when energized, are adapted to attract the armatures 15 and said armatures have the outer ends thereof provided with pins 19 extending into links 20 pivotally connected to cranks 21 of sector gears 22. Two of these links are slotted, as shown in Fig. 5. The sector gears are pivotally mounted upon pins 23 connecting the plates 12 and 13 and said gears mesh with a pinion 25 mounted upon an arbor or shaft 24 journaled in the plates 12 and 13. The shaft 24 protrudes 105 through an opening 26 in a partition or reflector plate 27 connected to the plate 13, as at 28.

110 Mounted upon the outer end of the shaft 24 is a spider 29 of an annular sign display member 30, said member being somewhat in the form of a disk having a central opening

31 at the inner side of a bull's eye or lens 7. The member 30 is provided with openings or apertures 32 in the form of characters, symbols or signs and these openings are covered by a sheet of translucent material 33 secured to the member 30, as best shown in Fig. 6.

The sign as shown in Fig. 3 consists of the words "Safety first", disposed to be normally displayed through the transparent plate 8 and this is accomplished by the springs 18* always restoring the armatures and sector gears to normal position.

In addition to the sign "Safety first" there is the word "Stop" and arrows adapted to be individually displayed to indicate direction of travel either to the right or to the left.

On the shaft 24 is a crank 25^a having side extensions 26^a and 27^a, also an extension 22^a. On the armatures 15 are stops 16^a, 16^b, 16^c. The stop 16^c is normally engaged by the extension 27^a so that the words "Safety first" are held at the opening in the front plate 4. The extension 22^a is adapted to pass by the stop 16^a, when the armature thereof is attracted or engage the stop and cause "Stop" to be displayed. The extension 22^a may also engage stop 16^b and extension 26^a may engage stop 16^c, thus displaying arrows.

Connected to the partition 27 of the reflector plate is a lamp socket 36 for an incandescent lamp 37 between the partition 27 and the member 30. This lamp is preferably located in the side of the signal casing and rays of light therefrom are reflected to the bull's eye or lens 7, which for purposes of a tail light is preferably red in color. Rays of light from the incandescent lamp 37 are also cast through a transparent plate 38 at one side of the shell 3, whereby a license card or sign may be illuminated at night.

The electro-magnets 17 constitute electrical devices adapted to actuate the sector gears 22 to rotate or rock the arbor or shaft 25, and said electrical devices are grounded as at 39, and connected by wires 40 to a switch 41. This switch may be of the pivoted lever type or in the form of a push button by which a plurality of contacts may be made to establish desired circuits. The switch 41 is connected to a suitable source of electrical energy, as a battery 42 and the incandescent lamp 37 is in circuit with the same source of electrical energy with a switch 43 interposed to control the illumination of the lamp.

The electro-mechanical mechanism located within the signal casing permits of the arm or shaft 25 being rotated a quarter of a revolution, a half of a revolution or three quarters of a revolution, according to which electro-magnet is energized by operating the

switch 41. It is through the medium of the slotted links 20 associated with two of the sector gears 22 that an electro-magnet may be selected to move the member 30 a desired distance, without materially effecting those armatures not brought into action, and immediately upon an electro-magnet being de-energized, the springs 18* restore the member 30 to normal position.

I attach considerable importance to the triangular housing for the sector gears 22 and their appurtenant parts, as this mechanism is compactly assembled to operate a single arbor or shaft common to all of the mechanism. The disposal of the mechanism also permits of a small cylindrical casing inclosing the same and such casing can be readily supported at the rear end of an automobile and finished to harmonize with other metallic fittings of the machine.

What I claim is:—

1. In an automobile traffic signal, a casing having a bull's eye and display opening, a rotary disk-like member adapted to display signs at the opening of said casing, a shaft for moving said member, sector gears about said shaft, adapted to partially rotate the same, and electrical devices for moving said sector gears.

2. An automobile traffic signal comprising a casing, having a display opening, a housing in said casing, a shaft journaled in said housing, a sign display member carried by said shaft and adapted to display signs at the opening of said casing, electro-magnets supported by said housing and disposed about said shaft, means including armatures actuated by said electro-magnets adapted to rotate said shaft predetermined distances, a crank on said shaft, and a stop on an armature of said electro-magnets adapted to be engaged by said crank to hold said shaft normally stationary with a sign of said member displayed at the opening of said casing.

3. A signal comprising a casing provided with a display opening, a rotary sign-display member in said casing adapted to display signs in the opening thereof, a shaft for rotating said member, sector gears about said shaft adapted to partially rotate said shaft, and electro-magnets having armatures connected to said sector gears and adapted to be individually energized to actuate said sector gears and impart movement to said member through said shaft.

In testimony whereof I affix my signature in presence of two witnesses.

HALLEY C. DOLAN.
